Attorneys

UNITED STATES PATENT OFFICE.

EUGENE LEE McGUIRE, OF MASSILLON, OHIO.

SIGN.

Application filed February 26, 1923. Serial No. 621,246.

To all whom it may concern:

Be it known that I, EUGENE L. McGUIRE, a citizen of the United States, residing at Massillon, in the county of Stark and State 5 of Ohio, have invented a new and useful Sign, of which the following is a specification.

This invention relates to changeable exhibitors and aims to provide an exhibitor 10 to be employed for advertising purposes, novel means being provided to support the exhibitor, whereby the same may be revolved by air pressure to attract attention.

Another object of the invention is to provide 15 an exhibitor which may be folded into a small and compact article for transportation and convenience in storing.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed, may be made within the scope of what is claimed, without departing from the spirit of the invention.

Referring to the drawing:

Figure 1 is a plan view of an exhibitor 30 constructed in accordance with the invention.

Figure 2 is a vertical sectional view through the exhibitor.

Figure 3 is a side elevational view thereof.

Figure 4 is a sectional view taken on line 35 4-4 of Figure 3.

Referring to the drawing in detail, the device embodies a base or supporting post indicated at 5, which may be formed of any 40 suitable material and provided with a bearing member in its upper end, the bearing member being indicated at 6 and provided with a shoulder to rest on the upper end of the member 5.

This bearing member is threaded internally 45 to receive the threaded extremity 7 of the support 8 which is in the form of a pipe threaded at its upper end as at 9 to accommodate the bearing 10 on which the exhibitor rotates.

The exhibitor includes rectangular exhibiting surfaces 11 which are formed pref-

erably of sheet metal and provided with flanges 12 extending at right angles to the surfaces thereof and defining pockets to 55 catch the wind and cause rotation of the sign proper. As shown, the inner ends of the members 11 are disposed adjacent to the upper extremity of the section 8 and are bolted to the bearing 10' at 12, while the 60 lower inner edges of the members 11 are bolted to the bearing 13, at 14, the bearing being mounted on the section 8 at a point adjacent to the upper end thereof.

The bearing 10' is formed with a hollow 65 portion to receive the tapered extremity 15 of the bearing 10, thereby providing bearings wherein the contacting surfaces thereof are relatively small to offer the least amount of resistance.

Bracing bars 16 are secured to the members 11 at the upper and lower edges thereof and at points adjacent to their outer ends, to brace the outer portions of the members 11 and hold them in proper spaced relation 75 with each other.

The inner ends of the members 11 are connected by the bars 17 that are bolted to the upper and lower edges thereof at 18, thereby holding the inner ends of the members 11 80 in proper spaced relation.

From the foregoing it will be seen that due to the construction as shown and described, advertising matter may be placed on the surfaces of the members 11, whereby the 85 device will be rotated by wind pressure, causing the various signs to be displayed at one side of the exhibitor.

What I claim as new is:

A movable sign including a supporting 90 post, a removable reduced end section positioned in the upper end of the supporting post, a tapered bearing member mounted on the upper end of the removable section, an exhibitor including relatively flat exhibiting 95 surfaces having flanges formed integral therewith, the flanges extending at right angles to the body portions of the exhibiting surfaces, means for connecting the upper and lower edges of adjacent exhibiting surfaces, 100 a bearing having connection with the adjacent inner edges of the exhibiting surfaces and adapted to receive the tapered bearing member of the removable end section, a

bearing secured between the adjacent inner edges of the exhibiting surfaces at points adjacent to the lower edges of the exhibiting surfaces, said last mentioned bearing adapted
5 to embrace a portion of the removable end section to restrict lateral movement of the exhibiting member.

In testimony that I claim the foregoing as my own, I have hereto affixed my signature in the presence of two witnesses.

EUGENE LEE McGUIRE.

Witnesses:

MILo VAN Fosson,
CHAS. F. BLAIR.
